UNITED STATES PATENT OFFICE

CLARA ROBERTS, OF NEWBERRY, MICHIGAN

CLOTHESLINE

Application filed November 14, 1929. Serial No. 407,185.

The present invention relates to clothes line hooks and more particularly to a hook which is adapted to be locked on a supporting structure either indoors or outdoors.

5 An object of this invention is to provide a hook of this character which is so constructed that it may be readily manufactured out of a single piece of wire of resilient structure.

10 Another object of this invention is to provide a clothes line hook which is adapted to be secured to one end of a clothes line and which embodies features permitting it to be readily snapped on to a supporting hook or looped clothes line.

15 The above and various other objects and advantages of this invention will in part be described and in part be understood from the following detailed description of the 20 present referred embodiment, the same being illustrated in the accompanying drawing wherein:—

Figure 1 is a detail perspective view of a hook constructed to the preferred embodiment of this invention; and

25 Figure 2 is a detail elevation showing the manner of using the hook herein disclosed on conventional supports.

In the drawing the numeral 15 designates 30 a conventional clothes line which is adapted to be mounted on supporting structures in the form of posts or hooks either indoors or outdoors.

At the present time there is available a 35 clothes line in the form of a looped line, that is a line having a plurality of depending loops and it is in order to provide a short or supplemental clothes line which may be readily positioned on the loop line that I 40 have devised, a hook which is hereinafter described, the object of this invention being to provide a hook which may be secured to each end of a short clothes line and which may be detachably positioned in the desired 45 loops on the main clothes line.

The numeral 17 designates generally a hook constructed according to the preferred embodiment of this invention, which is adapted to be secured to each end of a clothes line.

The hook member 17 may be constructed of metal, wire or the like and is preferably provided with a pair of loops or coils 18 which are adapted to engage one end of the short clothes line and are provided with a hook member 19 which is preferably formed integrally with the loops 18 by extending the wire outwardly and bending the wire backwardly to form the desired hook.

A locking member 20 is formed integrally 60 with the coils or loops 18 and extends outwardly therefrom, the upper end 21 of the locking member extending through and outwardly above the open ends of the hook 19 and between the coils 18. The hook member 17 is preferably formed of resilient material 65 so that the looped portion 18 thereof is formed into a spiral spring.

The locking member 20 is provided with a rearwardly extending releasing member 22 70 and is adapted to be engaged by the hand so as to spring the upper end 21 of the locking member rearwardly to permit the insertion of the wire or loop 12 therein.

The releasing member 22 is preferably provided with a looped lower end portion 23 to facilitate the insertion of a finger therein so that the releasing member 20 may be swung downwardly to permit the ready insertion of a hook or wire within the hook portion 19.

It is of course understood that various changes and modifications may be made in the details of construction and design of the above specifically described embodiment of the invention without departing from the spirit thereof, such changes and modifications being restricted only by the scope of the following claim.

What is claimed is:—

A clothes line hook of the character de- 90

scribed, comprising a pair of looped side members, connecting means for said members whereby to maintain said members in spaced relation to each other, eyes integrally formed with said members and adapted to receive an end of a clothes line, a resilient locking member integrally formed with one of said eyes and having one portion thereof normally disposed between said members, and releasing means carried by said locking member whereby to facilitate swinging of the said locking member into release position.

10 In testimony whereof I hereunto affix my signature.
